UNITED STATES PATENT OFFICE.

ERNEST L. FARROW AND HARRY GOODMAN, OF CLEVELAND, OHIO.

SPRING-MATTRESS.

1,205,135.

Specification of Letters Patent. Patented Nov. 14, 1916.

Application filed March 11, 1912. Serial No. 683,050.

To all whom it may concern:

Be it known that we, ERNEST L. FARROW and HARRY GOODMAN, citizens of the United States, residing at Cleveland, in the county 5 of Cuyahoga and State of Ohio, have invented certain new and useful Improvements in Spring-Mattresses, of which the following is a specification.

This invention has reference to an improvement in spring mattresses, and the invention consists in the construction and combination of parts, substantially as shown and described and particularly pointed out in the claim.

15 In the accompanying drawings, Figure 1 is a perspective view of our new and improved mattress, and Fig. 2, is an enlarged sectional elevation of a portion of the mattress. Fig. 3 is a plan view of a portion of 20 the spring wire interior portion or frame of the mattress and a section of the cushioning border at the left.

The mattress as thus shown is purposely built to have the size and appearance of the 25 usual hair mattress, so-called, the size and shape being about the same as such a mattress and also as light in weight and easily handled and reversible like a tufted hair mattress, but still giving a spring wire foundation in its middle. In fact the invention 30 lies in a construction which makes such a build of mattress possible and which, in the present case, comprises upper and lower or side meshes of wire built up with straight 35 strips or pieces of wire 2 and 3 interwoven at right angles to each other and more or less bent at their crossings or angles and spaced apart at intervals of about an inch and a half or two inches so as to give the 40 fabric or mesh all needed strength and yet keep it as light as possible. Practically the said meshes or sheets of wire fabric constitute the immediate foundation both for the covering on the outside and for the spiral 45 springs 5 on the inside which come between said sheets and are interwoven at their respective ends with the said cross wires 2 and 3. In respect to arrangement, each spring 50 centers axially and has its bearing over the intersection or crossing of two of said wires 2 and 3 while its coil is interwoven or run in with two side wires in each of the series of wires 2 and 3, thus giving said springs wide and uniform bearings at each end.

55 This makes a wire embodiment or framework of all spring material which in fact is

a complete article of manufacture in itself and usually is made in a factory devoted to such manufacture while the upholstering or padding work outside is generally done at 60 least in another department if not in a different factory and by an entirely different set of workmen. However, there is also this peculiarity in the said wire embodiment or frame that, after all, it is incomplete and not in the shape or condition in 65 which it is used because the springs 5 are not under tension. This is true because there is no wire or other means binding said sides together between the sides of the mattress to 70 which the springs are attached, except to give such tension and the only connection between said sides is the springs 5. Hence in order to render the said frame really available in the bed we require means to compress 75 the sides of the frame within the compass and shape substantially as shown in Figs. 1 and 2, and in which the springs especially are compressed to their sustaining tension.

It will be noticed in Fig. 2 that there is 80 only a perceptible difference in the elevation between the springs in the middle portion of the mattress and the edge at the left, but this difference also has its plan and advantage because persons will sit on the 85 edge of the mattress and it requires sustaining strength at this point not really demanded in the body of the bed, as is obvious. Hence the edge springs are and should be under greater tension than the interior 90 springs and are held in this way by a suitably heavy cover or inclosure 6. This cover is of strong woven fabric and designed to completely envelop the wire frame or structure and to be stretched over the same in 95 such way that it will press the two sides of the mattress together and compress all the springs more or less evenly, and in any event act upon the springs in such way as to give the mattress the proportions seen in 100 Fig. 1. This of course involves a cover of a suitable shape and size having side and end edges 7 that are comparatively narrow, say relatively as seen in Fig. 2, and as may be deducted from the edges of the mattress 105 seen in Fig. 1, making allowance for the padding on both sides and the rolls or beads 6 along said edges. To be more definite, these straight edge portions 7 in a full-sized mattress are only about five inches deep including padding, and the border springs, when compressed, are only about three 110

inches. The said cover or inclosure 6 is of course stretched over the said wire frame and serves to compress all the springs to the using tension. The complete effect however, 5 is about as illustrated in Figs. 1 and 2, with substantially flat sides, plus the increased depth by padding or upholstering over the body of the mattress as shown. Thus it will be seen that the top and bottom cross 10 wires of the spring extend beyond the edge springs and that the side edges of the spring casing or cover restrain the top and bottom cross wires in converging relation at the edges of the mattress to normally retain the 15 edge springs under greater compression than the interior springs. The said padding also may be of the usual kind with more or less curled hair 8 and cotton or other fibrous material 9 built into the same. As to this 20 the manufacturer may have his own choice and be governed by the demand for cheap or more expensive mattress, the all-hair mattress of course being regarded as probably of the best grade and of the highest price. 25 For our present purposes any suitable upholstering suffices, because the invention lies more particularly in the new and original spring wire base or frame and in the combination therewith of a compressing and 30 shaping inclosure or envelop of a suitable woven fabric which will also give outline to the mattress and provide a foundation for the padding as shown and described.

The net value of the invention is a mattress 35 which is the equivalent of an all-hair mattress but with a wire spring foundation which enables a cheaper and more resilient mattress to be made than one that is all hair or that is part hair and other padding 40 and which is exceptionally comfortable to occupy.

The rolls or beads *b* confine the edge wires 10, which are of the same gage and as light and springy as the wires 2 and 3, and therefore 45 need this reënforcing roll or bead, and the advantage to be gained thereby is a

springy-like edge to the mattress which will flex under weight and come back to straight lines again, thus preserving the shape of the mattress for a much longer period than if 50 relatively heavy border wires substituted light wires 10. The rolls or beads *b* and border wires 10 are fastened together at intervals by cords 12 or other suitable means.

A further feature of this bed mattress is 55 embodied in the air controlling and ventilating tubes 11 extending at intervals through the sides. The springs naturally expand the mattress to fixed limits and the air tubes not only ventilate the interior but admit air 60 slowly to permit full and complete expansion.

When the mattress is first occupied the air is in part slowly expelled, but in the meantime the air within acts as a cushion to 65 supplement the action of the springs. Tubes 11 are provided with minute air passages 14 preferably located at the outer end of the central bore 15, thus restricting the passage of air in fine degree and excluding vermin, 70 or other objectionable matter from entering the larger bore 15.

What we claim is:

A spring mattress comprising spiral wire springs arranged in series and a plurality 75 of cross wires top and bottom threaded at right angles through the same and extending beyond the edges of said springs, in combination with a woven fabric cover stretched tightly about said springs and 80 wire structure and restraining the top and bottom cross wires in converging relations at the edges of the mattress to normally retain the edge springs under greater compression than the interior springs. 85

In testimony whereof we affix our signatures in presence of two witnesses.

ERNEST L. FARROW.
HARRY GOODMAN.
